TAMPERPROOF CLOSURE SEAL

Solomon Grauer, Brooklyn, N. Y.

Application December 17, 1934, Serial No. 757,855

6 Claims. (Cl. 215—7)

The invention relates to seals of the type which is employed with various closure devices for indicating the initial removal of the closure device from its container. The invention has for its main objects to provide a seal which can be used in combination with containers and closure devices of various kinds and which will plainly indicate when once the closure has been removed from its container.

10 A further object is to provide a tamper-proof seal which may be placed on the container without any special tool equipment and with a minimum expenditure of time and labor. A further object is to provide a tamper-proof seal of simple and inexpensive construction. These and various other objects and advantages will be readily understood from the following description and from the accompanying drawing of preferred embodiments of the invention in which, however, 15 modifications may be made without departing from the scope of the appended claims. In the drawing

Fig. 1 is a fragmental, front view of a flask to which the invention has been applied;

25 Fig. 2 is a side view of Fig. 1;

Fig. 3 is a cross-sectional view, taken on line A—A in Fig. 1;

Fig. 4 is a top view of the tamper-proof seal;

30 Fig. 5 is a front view of the seal as it will appear after the closure has once been removed from the flask;

Fig. 6 is a front view of a jar to which the seal has been applied;

Fig. 7 is a modified adoption of the seal;

35 Fig. 8 is a fragmental view of an ordinary, cork-stoppered bottle to which the seal has been applied;

Fig. 9 is a cross-sectional view of a bottle neck showing a modification of the construction shown 40 in Fig. 3; and

Fig. 10 is a top view of the seal shown in Fig. 9.

Referring first to Figs. 1 to 5, inclusive, the neck of the flask is shown at 10 and the cap at 11. A recess 12 is formed in the neck. In this recess two shoulders 13 and 14 are formed. Two flat surfaces 15 and 16 are also formed in the recess. The seal consists of a semi-circular spring member 17 provided at its end with hooks 18 and 19.

50 The seal is also provided at its center with an upwardly extending arm 20. As shown, the seal is inserted in the recess 12 with the hooks engaging over the shoulders 13 and 14 and with the arm 20 extending upwardly. The extreme end 55 21 of the arm is bent in over the cap 11. The

point at which the seal proper and the arm 20 is connected is weakened, as shown at 22.

To attach the seal in the recess pressure is applied at the points indicated by the arrows in Fig. 3. When this pressure is released the hooks 18 and 19 engage behind the shoulders 13 and 14. Once the seal has been inserted in this manner it is impossible to remove it. As the arm 20 extends upwardly with its extreme end 10 15 21 projecting over the top of the cap, it is impossible to remove this cap without bending the arm. When this is attempted the arm will break off due to the weakening of the connection between the arm and the seal. Thus to remove the cap it is necessary to break off the arm, 15 this immediately indicates that the bottle has been opened. When the seal is used on bottles or flasks containing alcoholic liquors, where a revenue stamp is required, the revenue stamp 23 may be placed under the arm and the seal, 20 as shown in Fig. 1. Fig. 5 shows the seal after the arm 20 has been broken off, the small cross-hatched part 24 indicates the former connection between the seal and the arm.

Referring now to Fig. 6, in which a jar is 25 shown at 24 and its cover at 25, in this instance a similar seal 26 is employed and the arm 27 projects over the cover as in the case just described. Here again the joint 28 between the seal and the arm has been weakened so that 30 the arm must be broken off before the cover can be removed.

In Fig. 7 a bottle neck is shown at 29 and a cap at 30, while the seal is shown at 31. In this instance the arm has been dispensed with 35 but a flexible tape 32 is secured to the bottle cap with its loose end under the seal. In this case, when the cap 30 is removed the tape 32 has to be withdrawn from under the seal and cannot be put back under this seal once withdrawn. Thus 40 the disengagement of the tape from the seal discloses that the bottle has been opened. It is evident that the revenue stamp pasted over the cap might serve in place of the tape 32. In fact any instrumentalities which may be secured to 45 the cap and held under the seal would indicate the opening of the bottle once the cap has been removed.

In Fig. 8 a bottle neck is shown at 33, an ordinary cork-stopper at 34, the seal at 35 and 50 the arm at 36. In this instance the arm 36 has to be broken from the seal before the cork can be extracted.

In Figs. 9 and 10 a slightly modified construction is shown. In this case a recess 37 is formed 55

- in the bottle neck 38 and this recess terminates at its end in two sockets 39 and 40. The seal 41, instead of being provided with curved hooks as shown in Fig. 4, is provided with two inwardly bent prongs 42 and 43. These prongs engage in the sockets 39 and 40 and effectively secure the seal in the recess. The seal is provided with an upwardly extending arm 44 as in the previously described case.
- 10 In addition to the manner in which the seal is held in the recess, it will be noted that the seal itself is entirely contained within the recess and that the seal is substantially of the same size as the recess so as to practically fill it. Thus it is impossible to insert any implement between the edges of the recess and the seal to pry out the seal. Once the seal has been snapped into the recess it cannot be removed without destroying the bottle.
- 20 From the foregoing it will be seen that this seal may be used with any container in which a recess can be formed and on which a cap is used and that it effectively discloses the initial removal of the cap from the container.
- 25 Having described my invention and its objects what I claim as new and wish to protect by Letters Patent is:
1. A tamper-proof seal for containers comprising a spring member adapted to be inserted in a recess in a container and to extend substantially half way around the circumference of such container; the thickness of the spring member being less than the depth of such recess and the shape of the spring member being substantially the same as the shape of the recess; prongs provided at each end of said spring member and adapted to engage in sockets formed in the ends of the recess; and the spring member adapted to clamp a member secured to the closure device of the container in such a manner that this member will be withdrawn from the clamping engagement when the closure device is removed from the container.
  2. In combination with a container having a closure device and a recess located transversely a distance below said closure device and extending substantially half way around the circumference of the container; a tamper-proof seal of substantially the same size and shape as the said recess and of a lesser thickness than the depth of the recess; prongs provided at each end of said seal and adapted to permanently lock in sockets formed in the ends of the recess; and the seal adapted to clamp a member secured to the closure device of the container in such a manner that this member will be withdrawn from the clamping engagement when the closure device is removed from the container.
  3. In combination with a container having a closure cap and a recess located transversely a distance below said closure cap and extending substantially half way around the circumference of the container; a seal of substantially the same size and shape as the said recess and of a lesser thickness than the depth of the recess; the ends of said seal bent inwardly towards each other; sockets formed at the ends of said recess in which the bent ends of the seal are permanently locked when the seal is inserted in the recess; an upwardly extending arm associated with the said seal and having its free end bent over the closure cap to prevent its removal; and the connection between the seal and the arm so weakened that the arm will be broken off when bent to enable the closure cap to be removed from the container.
  4. In combination with a container having a stopper and a recess located transversely a distance below said stopper and extending substantially half way around the circumference of the container; a seal of substantially the same size and shape as the said recess and of a lesser thickness than the depth of the recess; the ends of said seal bent inwardly towards each other; sockets formed at the ends of said recess in which the bent ends of the seal are permanently locked when the seal is inserted in the recess; an upwardly extending arm associated with the seal and having its free end bent over the stopper to prevent its removal; and the connection between the seal and the arm so weakened that the arm will be broken off when bent to enable the stopper to be removed from the container.
  5. In combination with a container having a closure device and a recess located transversely a distance below said closure cap and extending substantially half way around the circumference of the container; a seal of substantially the same size and shape as the said recess and of a lesser thickness than the depth of the recess; the ends of said seal bent inwardly towards each other; sockets formed at the ends of said recess in which the bent ends of the seal are permanently locked when the seal is inserted in the recess; an upwardly extending arm associated with the seal and having its free end bent over the closure device to prevent its removal; the connection between the seal and the arm so weakened that the arm will be broken off when bent to enable the closure device to be removed from the container; and a paper strip secured over the top of the closure device with one of its ends clamped under the seal in the recess.
  6. A tamper-proof seal for containers comprising a spring member adapted to be inserted in a transverse recess in a container and extending substantially half way around the circumference of said container; the shape of the spring member being substantially the same as the shape of the recess; prongs provided at each end of said spring member and adapted to be permanently locked in sockets formed in the ends of said transverse recess; an upwardly extending arm associated with said spring member and having its free end bent over to engage with the closure device of the container to prevent its removal; and the connection between the seal and the arm so weakened that the arm will be broken off when bent to enable the closure device to be removable from the container.

SOLOMON GRAUER. 65
